UNITED STATES PATENT OFFICE.

JENNIE L. BRIGGS, OF TAUNTON, MASSACHUSETTS.

DESIGN FOR A SHIRT-WAIST FASTENER.

SPECIFICATION forming part of Design No. 31,431, dated August 22, 1899.

Application filed April 12, 1899. Serial No. 712,805. Term of patent 7 years.

To all whom it may concern:

Be it known that I, JENNIE L. BRIGGS, of Taunton, in the county of Bristol and State of Massachusetts, have invented and produced 5 a new and original Design for a Shirt-Waist Fastener, of which the following is a specification, reference being had to the accompanying drawings, forming part thereof.

Figure 1 is a perspective view of a stud 10 adapted for use on shirts or waists, showing my design. Fig. 2 is a sectional view of the same.

The leading feature of my design consists 15 in the bar, the ends of which extend at right angles to the bar and support two buttons, the plane of which is parallel to the plane of the connecting-bar.

In the drawings, *a* indicates the straight 20 bar, *b* posts extending at right angles to the bar, *c c* the buttons or studs, which are

of circular outline and of convex cross-section. The central disk is surrounded by an annular inclined marginal border ornamented with a beaded pattern. The two buttons or studs *c c* are on a plane with the straight bar 25 *a* and are maintained in this position when worn on a shirt or waist, presenting to the eye the face view of the studs or buttons.

Having thus described my invention, what I claim as new, and desire to secure by Letters 30 Patent, is—

The design for a shirt-waist fastener herein shown and described.

In witness whereof I have hereunto set my hand.

JENNIE L. BRIGGS.
